ENVELOPE FEED MECHANISM

Lester A. Cherry, Kenmore, and Clarence N. Fuller, Indian Falls, N. Y., assignors to H. W. Hilliard Co. Inc., Buffalo, N. Y., a corporation of New York

Application May 27, 1935, Serial No. 23,626

10 Claims. (Cl. 271—2)

This invention relates to improvements in envelope feed mechanisms of the kind which are associated with apparatus in which preformed envelopes are conditioned in accordance with their intended use and more particularly the invention is concerned with apparatus having a magazine in which the envelopes are arranged in an inverted position with their sealing flaps extending forwardly, the associated feed mechanism including fold engaging elements which are adapted to enter between the sealing flap and the body of the envelope to withdraw the envelopes one at a time from the magazine.

The principal object of the invention is a mechanism of the kind generally described in which provision is made for facilitating entry of the fold engaging elements between the flap and the body of the envelope, whereby to insure withdrawal of the envelopes from the magazine at regular predetermined intervals regardless of the proximity of the flaps to the bodies of the envelopes.

A further object is to provide a mechanism which is adjustable to accommodate envelopes of various sizes.

The invention is illustrated in the accompanying drawings in which:

Figure 1 is a view partially in elevation and partially in section illustrating the feed mechanism in connection with a machine for affixing opening threads to envelopes.

Figure 2 is a similar view in which the feed mechanism is shown moving an envelope from the magazine to the carrier upon which the envelope is to be secured during the thread affixing operations.

Figure 3 is a front elevation of that part of the machine shown in Figure 1.

Figure 4 is a fragmentary section of the feed mechanism and is taken along line 4—4 of Figure 1.

Figure 5 is a fragmentary perspective view of the feed mechanism.

Figure 6 is a fragmentary perspective view of an envelope and illustrates the action of one of the elements which is adapted to open the flap of the envelope to insure entry of the fold engaging fingers between it and the body of the envelope.

Figure 7 is a section along line 7—7 of Figure 6.

Figure 8 is a section similar to Figure 7 showing the flap of the envelope being held open while one of the fold engaging fingers has been moved between the flap and the body of the envelope.

Figure 9 is a section taken along line 9—9 of Figure 8.

Figure 10 is a perspective view of the essential parts of the feed mechanism and shows the flap of an envelope being held open as the fold engaging fingers move downwardly to withdraw the envelope from the magazine.

Figure 11 is a perspective view of the same parts illustrating the positions of the flap opening elements prior to their movement beneath the flap of the next succeeding envelope in the magazine.

The invention is illustrated, by way of example, in connection with a machine which forms the subject matter of Patent Number 1,966,333, granted to Lester A. Cherry and Clarence N. Fuller, the said machine being adapted to affix a thread to an envelope along the fold connecting the flap and the body of the envelope, whereby the envelope may be slit along the fold to enable removal of its contents by pulling the protruding end of the thread substantially transversely of the fold.

In general the machine of the patent includes an envelope magazine, envelope feed mechanism and a rotor which carries a circular series of envelope receiving units. The rotor is revolved step-by-step to move the said units successively to an envelope receiving position with respect to the magazine, the feed mechanism being operative to withdraw an envelope from the magazine and deposit it upon a unit as the latter pauses at the envelope receiving position. The envelope is secured to the unit and as the rotor revolves the following operations are performed in the order named: (1) the sealing flap is opened and is held in this position; (2) the envelope is moved to a position in which a continuous thread to which an adhesive has been applied lies adjacent the juncture of the flap and the body of the envelope; (3) the sealing flap is folded upon, and pressed against a section of the said thread; (4) the thread is severed at a point beyond one end of the envelope so as to provide a protruding portion; and (5) the envelope is released and removed from the rotor.

The machine is sufficiently indicated by a showing of the upper ends of the side members 15 and 16 of the framework in which the various mechanisms are supported and the rotor which is suitably supported in the said frame work is indicated at 17. The said rotor includes a series of similar envelope receiving units 18 which, as illustrated, are spaced 45° apart and as it revolves step-by-step the envelope receiving units are moved successively to a position beneath an en-

velope magazine 19. The latter is carried by cross rod 20 which is supported from a member 21 by arms 22, the said member being mounted between the side frame members 15 and 16. The 5 magazine includes a bottom plate 19a, inclined rods 23 upon which the envelopes E are arranged in an inverted position with their sealing flaps E' extending forwardly and side guide rails 24, the upper surface of the bottom plate 19a being flush 10 with the top faces of the rods 23. A follower 25, which is arranged in the magazine behind the envelopes, is adapted to cause the envelopes to move toward the lower end of the magazine as the envelopes in the forward end are withdrawn, the 15 upper edge of the foremost envelope engaging a depending stop 26 while the lower edge of the said envelope is engaged between the rounded forward edge of the plate 19a and a resilient member 27. The stop 26 and member 27 are carried by 20 an element 28 which is mounted upon a rod 29, the said rod being supported from the member 20 by arms 30.

The mechanism for withdrawing the envelopes from the magazine 19 and depositing them upon the rotor 17 includes a pair of arms 31 which are carried by a shaft 32, the said arms being provided with fingers 33 which lie at opposite sides of the resilient member 27. The shaft 32 is mounted between the side frame members 15 and 16 and is formed at one end with an extension 34. The latter carries a crank 35 which is connected by a rod 36 to a crosshead 37. A cam wheel 38 is carried by an extension 39 of the main cam shaft of the machine, the said extension also carrying a loosely mounted block 40 which is suitably grooved at its opposite sides to provide guideways for the opposite sides of the crosshead. The said crosshead carries a roller 41 which is located in a continuous groove 42 formed in the cam wheel 38. 40 It will be apparent that as the cam wheel 38 is caused to rotate the roller 41 will follow the groove 42 and impart a reciprocating movement to the crosshead 37. The shaft 32 will, therefore, be oscillated through a predetermined angle as will 45 the arms 31 and the fingers 33. The parts are so designed that when the arms 31 are at the upper limit of their range of movement the fingers 33 are located above the sealing flap of the foremost envelope in the magazine, the ends of the 50 said fingers being held lightly against the body of the said envelope. As the arms 31 start to move downwardly the fingers 33 enter between the flap and the body of the envelope and engage the fold connecting these parts at opposite sides 55 of the envelope. During the remainder of the downward movement of the arms 31, therefore, the fingers 33 carry the envelope with them, the envelope coming to rest upon one of the envelope receiving units 18 as the arms 31 reach the lower 60 limit of their range of movement. In its movement from the magazine to the envelope receiving unit the envelope moves between a resilient member 43 and a curved plate 43a. The former is carried by the element 28 and serves to hold the 65 envelope lightly against the latter, the said plate being supported from a transverse shaft 44. The slight resistance thus offered to the movement of the envelope serves to hold the latter in co-operating relation with the fingers 33. Each of the 70 units 18 includes a pair of gripping elements 45 which are movable, when the unit is in an envelope receiving position, to permit an envelope to be passed beneath them. Thereafter they are movable to engage the envelope at its opposite 75 sides, whereby to secure it upon the unit during

the subsequent thread affixing operations. In this connection it is understood, of course, that the withdrawal of an envelope from the magazine 19 and its securement upon one of the envelope receiving units is effected while the rotor 5 is at rest and that immediately after an envelope has been secured upon a unit in the manner described the rotor revolves through an angle of 45° to move the succeeding unit to an envelope receiving position. 10

After an envelope has been secured upon an envelope receiving unit, the latter is moved step-by-step toward the station at which the envelope is to be released and removed from the rotor. During such movements of the unit the flap of 15 the envelope is opened and the envelope is moved so that the fold connecting the flap and the body lies alongside a section of a continuous thread 46 (Figure 1). Thereafter the flap is closed over, and pressed against, the section of thread beneath it to insure adherence of the thread to the envelope, the thread being cut off beyond the end of the envelope to provide a protruding portion which may be grasped and pulled when the envelope is to be opened. 20 25

The invention contemplates the use of means for opening the flap of the foremost envelope in the magazine 19 prior to the downward movement of the arms 31, whereby to insure entry of the fingers 33 between the flap and the body of 30 the envelope. The said means is carried by a cross member 47 which is supported from the cross rod 20 by rods 48 and 49 and includes a pair of blade-like elements 50 and 51. The element 50 is fixed to the outer end of a shaft 52 35 while the element 51 is fixed to the outer end of a similar shaft 53, the said elements lying at opposite sides of the member 27 and being angularly inclined, with respect to their width, so that the inner edges of their lower ends lightly engage 40 the envelope body while the outer edges of the said ends are spaced from said body. The shafts 52 and 53 pass through and are journaled in the cross member 47 and they carry gears 54 and 55, respectively, which are fixed to their inner ends. 45 The gear 54 meshes with a gear 56 while the gear 55 meshes with a similar gear 57, the gears 56 and 57 being fixed to an auxiliary shaft 58 which is journaled at its opposite ends in rearwardly extending arms 59 formed or provided at opposite 50 ends of the cross member 47. A crank 60 is fixed to one end of the auxiliary shaft 58 and is connected by a link 61 to a crank 62 which is fixed to the shaft 32. 55

It will be apparent that as the shaft 32 is oscillated to move the arms 31 in the manner described, the oscillating movement of the said shaft will be transmitted by the crank 62, link 61 and crank 60 to the auxiliary shaft 58, thereby causing the lower ends of the elements 50 and 51 to move toward and away from one another. The said elements are adjusted upon their respective shafts so that when their lower ends are farthest from one another they lie beyond the ends of the sealing flap of the foremost envelope in the magazine as illustrated in Figure 11 while the cross member 47 is adjusted upon the rods 48 and 49 so that as the lower ends of the elements 50 and 51 move toward one another they pass beneath the ends of the sealing flap, the said elements 65 lightly engaging the body of the envelope during such movement. As the ends of the said elements pass beneath the sealing flap and move toward the central portion of the envelope the sealing flap is moved outwardly with respect to 70 75 80 85 90 95 98 99 100

the envelope body, the extent to which the sealing flap is opened depending, of course, upon the width of the elements and their angle of inclination. Preferably the leading edges of the elements 5 are of a blade-like character so that their passage beneath the sealing flap is insured even though the flap lies closely against the envelope body.

The movement of the elements 50 and 51 is so timed that when the arms 31 are at the upper limit of their range of movement the lower ends of the said elements have been moved to open the sealing flap of the foremost envelope in the magazine, the said elements occupying the position illustrated in Figure 10. When the arms 31 are at the upper limit of their range of movement the fingers 33 are only a short distance above the sealing flap of the envelope. Hence during the initial part of the downward movement 10 of the arms 31 the fingers 33 move between the flap and the body of the envelope and engage the fold connecting these parts. Hence as the arms 31 continue to move downwardly the fingers 33 carry the envelope with it. The lower ends 15 of the elements 50 and 51 move away from one another during the downward movement of the arms 31, it being noted that as the fingers 33 pass behind the sealing flap of the envelope during the initial part of the downward movement of 20 the arms 31 the said sealing flap is held open at this time. The lower ends of the elements 50 and 51 reach the limit of their movement away from one another as the arms 31 reach the limit of their 25 downward movement. Hence as an envelope is deposited upon an envelope receiving unit the lower ends of the elements 50 and 51 are located adjacent the opposite ends of the sealing flap of the succeeding envelope in the magazine. During the upward, or return, movement of the 30 arms 31, therefore, the lower ends of the said elements move between the flap and body of the envelope and open the flap, whereby during the following downward movement of the arms 31 the fingers 33 will pass behind the sealing flap 35 of the envelope and withdraw it from the magazine in the manner described.

From the foregoing it will be apparent that the sealing flap of the foremost envelope in the magazine will be partially opened, prior to the downward movement of the arms 31, whereby the fingers 33 will pass behind the sealing flap regardless of its original proximity to the body of the envelope. The mechanism has the advantage that it is adjustable to accommodate envelopes 40 of varying sizes, it being noted in this connection that the distance between the lower ends of the elements 50 and 51 may be increased or decreased, at will, by adjusting the elements angularly upon the shafts 52 and 53 while the cross member 47 45 may be adjusted lengthwise of the rods 48 and 49 to compensate for sealing flaps of varying widths.

Although the mechanism is illustrated in connection with apparatus for affixing opening threads to envelopes, the invention is not limited to this specific application, it being understood that the mechanism may be employed, with its attendant advantages, in connection with any apparatus in which the envelopes are withdrawn 50 one at a time from the associated magazine.

We claim as our invention:

1. The combination with apparatus to which preformed envelopes are to be delivered and a magazine in which the envelopes are arranged 55 with their sealing flaps extending forwardly, of

mechanism for withdrawing said envelopes from said magazine and delivering them one at a time to said apparatus, said mechanism including means which is movable to enter between the sealing flap and the body of the foremost envelope in said magazine to engage the fold connecting the sealing flap and body and which is thereafter movable further in the same direction to withdraw said envelope from said magazine and means which is movable between said flap and 10 said body to partially open said flap, whereby to facilitate entry of said first named means between said flap and said body.

2. The combination with apparatus to which preformed envelopes are to be delivered and a magazine in which the envelopes are arranged with their sealing flaps extending forwardly, of mechanism for withdrawing said envelopes from said magazine and delivering them one at a time to said apparatus, said mechanism including 15 means which is movable in two directions and which is adapted, during the initial part of its movement in one direction, to enter between the sealing flap and the body of the foremost envelope in said magazine to engage the fold connecting the sealing flap and body, whereby to withdraw said envelope from said magazine during its further movement in the same direction and means which is movable between said flap and 20 said body to partially open said flap, whereby to facilitate entry of said first named means between said flap and said body.

3. The combination with apparatus to which preformed envelopes are to be delivered and a magazine in which the envelopes are arranged with their sealing flaps extending forwardly, of mechanism for withdrawing said envelopes from said magazine and delivering them one at a time to said apparatus, said mechanism including 25 means which is movable in two directions and which are adapted, during the initial part of their movement in one direction, to enter between the sealing flap and the body of the foremost envelope in said magazine to engage the fold connecting the sealing flap and body at opposite sides 30 of the body, whereby to withdraw said envelope from said magazine during further movement of said fingers in the same direction and means which is movable between said flap and said body to partially open said flap, whereby to facilitate 35 entry of said fingers between said flap and said body.

4. The combination with apparatus to which preformed envelopes are to be delivered and a magazine in which the envelopes are arranged with their sealing flaps extending forwardly, of mechanism for withdrawing said envelopes from said magazine and delivering them one at a time to said apparatus, said mechanism including 40 means which is movable in two directions and which is adapted, during the initial part of its movement in one direction to enter between the sealing flap and the body of the foremost envelope in said magazine to engage the fold connecting the sealing flap and body, whereby to withdraw said envelope from said magazine during its further movement in the same direction and co-operating pivotally mounted elements 45 which are movable to partially open said sealing flap prior to the initial movement of said means.

5. The combination with apparatus to which preformed envelopes are to be delivered and a magazine in which the envelopes are arranged with their sealing flaps extending forwardly, of mechanism for withdrawing said envelopes from 50

said magazine and delivering them one at a time to said apparatus, said mechanism including fingers which are movable in two directions and which are adapted, during the initial part of 5 their movement in one direction, to enter between the sealing flap and the body of the foremost envelope in said magazine to engage the fold connecting the sealing flap and body at opposite sides of the body, whereby to withdraw 10 said envelope from said magazine during the further movement of said fingers in the same direction and co-operating pivotally mounted elements which are movable to partially open said sealing flap prior to the initial movement of said 15 fingers.

6. The combination with apparatus to which preformed envelopes are to be delivered and a magazine in which the envelopes are arranged with their sealing flaps extending forwardly, of 20 mechanism for withdrawing said envelopes from said magazine and delivering them one at a time to said apparatus, said mechanism including fingers which are movable in two directions and which are adapted, during the initial part of 25 their movement in one direction, to enter between the sealing flap and the body of the foremost envelope in said magazine to engage the fold connecting the sealing flap and body at opposite sides of the body, whereby to withdraw 30 said envelope from said magazine during the further movement of said fingers in the same direction and co-operating pivotally mounted elements which are movable to partially open said sealing flap prior to the initial movement of said 35 fingers, said fingers being angularly inclined relative to the body of the envelope and having their inwardly directed edges lightly engaging the body.

7. The combination with apparatus to which 40 preformed envelopes are to be delivered and a magazine in which the envelopes are arranged with their sealing flaps extending forwardly, of mechanism for withdrawing said envelopes from said magazine and delivering them one at a time to said apparatus, said mechanism including fingers which are movable in two directions and which are adapted, during the initial part of 45 their movement in one direction, to enter between the sealing flap and the body of the foremost envelope in said magazine to engage the fold connecting the sealing flap and body at opposite sides of the body, whereby to withdraw 50 said envelope from said magazine during the further movement of said fingers in the same direction and co-operating pivotally mounted elements which are movable to partially open said sealing flap prior to the initial movement of said 55 means, the lower ends of said elements being located behind said sealing flap substantially 60 midway between the ends of said envelope when said fingers engage said fold.

8. The combination with apparatus to which 65 preformed envelopes are adapted to be delivered and a magazine in which the envelopes are arranged with their sealing flaps extending forwardly, of mechanism for withdrawing said envelopes from said magazine and delivering them one at a time to said apparatus, said mechanism including a shaft, means for oscillating said shaft between predetermined limits, a pair of arms 70 fixed to said shaft, said arms carrying fingers which are adapted, during the initial part of the movement of said arms in one direction, to enter between the sealing flap and the body of the 75 foremost envelope in said magazine to engage

the fold connecting the sealing flap and body at opposite sides of the body, whereby to withdraw said envelope from said magazine during the further movement of said arms in the same direction and co-operating pivotally mounted elements 5 which are movable to partially open said sealing flap to facilitate entry of said fingers between it and said body and means connecting said shaft with said elements whereby they are actuated to partially open said sealing flap prior to the 10 initial movement of said arms.

9. The combination with apparatus to which preformed envelopes are adapted to be delivered and a magazine in which the envelopes are arranged with their sealing flaps extending forwardly, of mechanism for withdrawing said envelopes from said magazine and delivering them one at a time to said apparatus, said mechanism including a shaft, means for oscillating said shaft between predetermined limits, a pair of arms 20 fixed to said shaft, said arms carrying fingers which are adapted, during the initial part of the movement of said arms in one direction, to enter between the sealing flap and the body of the foremost envelope in said magazine to engage the 25 fold connecting the sealing flap and the body at opposite sides of the body, whereby to withdraw said envelope from said magazine during the further movement of said arms in the same direction and co-operating pivotally mounted 30 elements which are movable to partially open said sealing flap, said elements being inclined in the direction of their width and having their inwardly directed edges lightly engaging the body of the envelope and means connecting said 35 shaft with said elements, whereby they are actuated to partially open said sealing flap prior to the initial movement of said arms.

10. The combination with apparatus to which preformed envelopes are adapted to be delivered 40 and a magazine in which the envelopes are arranged with their sealing flaps extending forwardly, of mechanism for withdrawing said envelopes from said magazine and delivering them one at a time to said apparatus, said mechanism 45 including a shaft, means for oscillating said shaft between predetermined limits, a pair of arms fixed to said shaft, said arms carrying fingers which are adapted, during the initial part of the movement of said arms in one direction, to enter 50 between the sealing flap and the body of the foremost envelope in said magazine to engage the fold connecting the sealing flap and body at opposite sides of the body, whereby to withdraw said envelope from said magazine during the further 55 movement of said arms in the same direction and cooperating elements which are adapted to partially open said sealing flap, actuating shafts which support said elements for pivotal movement, a gear carried by each of said actuating 60 shafts, an auxiliary shaft, gears carried by said auxiliary shaft which mesh with said first mentioned gears and means connecting said first mentioned shaft with said auxiliary shaft, whereby the lower ends of said elements are caused to 65 move toward and away from one another, said elements lightly engaging the foremost envelope in said magazine during such movement and being so timed that they move behind the sealing flap of said envelope to partially open it prior 70 to the initial movement of said arms.

LESTER A. CHERRY.
CLARENCE N. FULLER.
